(57) **CLAIM**

I claim the ornamental design for an electric measuring device, as shown and described herein.

DESCRIPTION

FIG. 1 is a perspective view of the electric measuring device showing my new design;

FIG. 2 is a front view thereof;

FIG. 3 is a back view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines appearing in the drawings are directed to environment and are for illustrative purposes only; the broken lines form no part of the claimed design.
